UNITED STATES PATENT OFFICE

WILLIAM A. SCHUTT, OF LITCHFIELD, ILLINOIS

HIGHWAY SIGN

Application filed February 18, 1932. Serial No. 593,718.

This invention relates to highway signs; and consists in the novel construction herein-after disclosed.

An object of the invention is to provide a sign having a supporting standard which may be readily driven into the ground at convenient places for display, with provision for supporting duplicate standard signs in the frame of the structure.

10 Another object of the invention is to provide a structure of the class referred to which may be economically manufactured and which will be durable in use.

15 Additional detailed advantages of the construction will be apparent from the following description thereof, taken in connection with the accompanying drawings, in which—

Fig. 1 is a front view.

20 Fig. 2 is an edge view.

Fig. 3 is a section taken substantially on the line 3—3 of Fig. 1.

Fig. 4 is a section taken substantially on the line 4—4 of Fig. 1.

25 Fig. 5 is a section taken substantially on the line 5—5 of Fig. 1.

Fig. 6 is a section taken substantially on the line 6—6 of Fig. 1.

Fig. 7 is a cross-section taken substantially on the line 7—7 of Fig. 1.

30 In the embodiment of the invention illustrated in the drawings, the standard is formed from an angle iron 1 extending the full length of the standard. The wings of the angle iron are turned outwardly and, at the lower sec-

35 tion, has connected therewith an angle piece 2 with the wings projecting in an opposite direction. The lower end of the standard is pointed as at 3. The length of the section 2 is approximately the depth to which the

40 standard is to be driven. Since the section 2 is connected to the lower part of the member 1 by welding or other suitable means, a very strong stake portion is provided. The four

45 wings of the lower portion afford a large surface contact and prevent the standard from being displaced after having been driven into the ground. The top edge of the member 2 provides a guide to indicate the proper depth to which the end of the standard should be

50 seated to constitute the sign support. At the

upper end of the member 1 is a plate 4 connected to the upper end of the member 1 by forming a transverse slot through the two wings thereof in which the plate 4 is seated. The plate is then preferably welded to provide a tight joint with the upper end of the standard. The plate 4 is provided with bolt openings 5 adjacent to each extremity.

55 The frame member is preferably formed of sheet metal and includes side members 6 formed from inwardly folded strips, thereby providing a channel portion between the folds of the strips. The frame further includes top and bottom members 7, the said members 7 being formed from longitudinal strips folded at one end and arranged to overlie the ends of the members 6. The free ends of the members 7 are overturned and are welded together, forming a continuous open slot along the top edge and along the lower edge of the sign frame. The plate 4 is inserted between the two folds of the member 7 at the bottom of the frame and the frame is bolted to the plate 4 by bolts 8 passing through openings in the folds of the member 7 and through the openings 5 in the plate 4.

60 The sign members 9 are arranged back to back and inserted in the upper part of the frame through the open slot between the folds of the members 7 at the upper part of the frame, the side edges of the sign members seating in the channels formed by the members 6, and the lower end of the sign members resting upon the upper edge of the plate 4.

65 There is thus provided a sign frame in which the signs of standard form displayed on sheet metal may be turned back to back and displayed on both sides of the frame. After the standard and frame are set up in a permanent location, the display matter may be 90 readily changed by removal of the signs from the frame and inserting new ones when desired.

70 The construction is useful as a highway sign for advertising and other purposes where it is desired to have a durable construction that may be easily set up in a permanent location and the signs changed for advertising purposes from time to time.

75 I am aware that the construction may be 100

modified in certain particulars without departing from the spirit and scope thereof. I do not limit myself, therefore, to the exact construction shown and described, but what I claim and desire to secure by Letters Patent is:—

- 5 1. A sign construction comprising a standard formed from a continuous length of angle iron and having slots in its upper end, a separate shorter length of angle iron integrally united to the lower end of said standard with the wings thereof arranged in opposite directions, a plate supported by the upper part of the standard and seated in said slots, and a sign frame removably connected with said plate.
- 10 2. A knock-down sign construction comprising an angle metal standard adapted to be driven into the ground, said standard having slots in its upper end, a plate supported by the upper part of said standard and seating in said slots, a sign frame, and disconnectable connections between said plate and said frame.
